(57) **CLAIM**

The ornamental design for a half moon type net, as shown and described.

DESCRIPTION

FIG. 1 is a perspective view of a half moon type net showing my new design;

FIG. 2 is a front elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a perspective view of a second embodiment of FIG. 1; and,

FIG. 8 is perspective view of a third embodiment of FIG. 1. The broken lines showing environment is for illustrative purpose only and forms no part of the claimed design.
